(57) **CLAIM**

The ornamental design for the water sports board, as shown and described.

DESCRIPTION

FIG. 1 is a perspective front view of the water sports board, which embodies my design;

FIG. 2 is a perspective rear view thereof;

FIG. 3 is a top elevation view thereof;

FIG. 4 is a rear elevation view thereof;

FIG. 5 is a left side view thereof;

FIG. 6 is a right side view thereof;

FIG. 7 is a front view thereof; and,

FIG. 8 is a rear view thereof.

The broken lines in the drawings depict portions of the water sports board that form no part of the claimed design.

1 Claim, 6 Drawing Sheets
